ASH RECEIVER

John Visser, Grand Rapids, Mich., assignor to
F. L. Jacobs Co., Detroit, Mich., a corporation
of Michigan

Application May 15, 1940, Serial No. 235,215

6 Claims. (Cl. 206—19.5)

My invention relates to ash receivers for use in automobiles and similar places. The ash receiver of this invention relates particularly to improvements in the type of ash receiver which is mounted behind an opening in a panel, the opening being provided with a door or closure for closing it when the ash receiver is not in use. More particularly, this invention relates to ash receivers mounted behind sliding doors or closures.

An important object of this invention is to eliminate rattles so prevalent in ash receivers of this type when the automobile is in operation.

Another object of this invention is to greatly improve the action of the sliding door during its sliding movement.

A further object of this invention is to provide means for resiliently and frictionally holding the sliding doors in any desired position and to avoid rattles in any such position.

Another object of this invention is to reduce the sliding friction incident to the sliding movements of the ash receiver doors or closures to a minimum.

A further object of this invention is to positively stop the movements of the ash receiver closures at predetermined points in their travel.

Another object of this invention is to provide a simple means for supporting and guiding a sliding door or closure into and out of an opening in a panel and for supporting an ash receptacle behind said opening.

A still further object of my invention is to provide an ash receiver which may be readily made from stamped metal parts so that large quantities may be rapidly produced in exact duplication one with another at a low cost and yet obtain the above objects.

One of the principal features of my invention is the provision of one or more curved doors or closures sliding in a curved track arranged so that the doors or closures, when in their closed position, lie substantially level with the panel and lie in back of the panel when in their open position.

Another feature of the present invention is the provision of a curved track or guideway for sliding doors or closures which also serves as a support for a removable ash receptacle.

These and other objects and features of my invention will be apparent from the following description and the accompanying drawings. My invention itself, however, both as to its organization and manner of construction, together with further objects and advantages thereof, may

best be understood by reference to the following description, taken in connection with the accompanying drawings, in which:

Figure 1 is a plan view of one of the preferred forms of the invention mounted in a portion of a panel;

Figure 2 is a longitudinal section on the line II—II of Figure 1, looking in the direction of the arrows;

Figure 3 is a cross section on the line III—III of Figure 1, looking in the direction of the arrows;

Figure 4 is a cross section on the line IV—IV of Figure 1, looking in the direction of the arrows;

Figure 5 is a plan view, similar to Figure 1, of another form of the invention;

Figure 6 is a longitudinal section on the line VI—VI of Figure 5, looking in the direction of the arrows;

Figure 7 is a cross section on the line VII—VII of Figure 5, looking in the direction of the arrows;

Figure 8 is a cross section on the line VIII—VIII of Figure 5, looking in the direction of the arrows, and

Figure 9 is a cross section of a third form of the invention, the cross section being taken just beyond the end of the ash receptacle.

The form of the invention shown in Figures 1 to 4 comprises a panel 10 which is generally horizontal and may form a portion of an automobile body, such as the horizontal portion of the instrument panel member lying immediately in back of the windshield in some automobile bodies. The panel 10 is generally flat, but its central portion is slightly arched, the width of the arched portion 11 being substantially equal to and coincident with the ends of a rectangular opening 12 in the panel. A pair of opposed curved channels or tracks 13 extend one along each side of the opening 12 in the panel and project under the flat parts of the panel 10 beyond each end of the opening 12. The channels 13 receive the edges of two sliding doors 14, which have the same curvature as the channels 13 and the arched portion 11 of the panel and whose main

or central portions between the channels 13 are raised level with the upper flanges 13a of the channels. Thus, the curved portion 11 of the panel 10, the upper flanges 13a of the channels 13, and the main portions of the doors 14, form a substantially even surface.

The channels 13 are formed along the two sides of an elongated curved mounting panel 15 stamped from a single piece of sheet metal and having a rectangular opening 16 slightly smaller than, and centered with respect to, the open-

ing 12 in the panel 10. The opening 16 in the mounting panel receives a round bottomed ash receptacle 17, which is generally rectangular in plan, and which is formed with an outwardly turned or rolled edge 18 adapted to rest upon the upper side of the retainer 15 around the opening 16. The receptacle 17 is resiliently held in place in the mounting panel 15 by means of four spring fingers 19 which extend down from the edges of the opening 16 in the retainer and press against the sides of the receptacle 17, as shown in Figure 2 and 4. Removal of the receptacle 17 from the mounting panel 15, for the purpose of emptying it of the ashes which it may contain, is facilitated by means of a snuffer 20, which is mounted within the receptacle 17, and which may serve as a handle for withdrawing the receptacle 17 from the mounting panel 15.

The mounting panel 15 is held in place by four lugs 21 spot welded to its under surface at either side of the opening for the receptacle 17 and extending out under the panel 10. The lugs 21 are secured by screws 22 to ears 23 formed on the edges of a frame 24 fixed to the under surface of the panel 10. The frame 24, which may be in two separate sections, as shown, or in a single section, is in the form of a ring fitting around the opening 12 in the panel 10 and is secured thereto by spot welding and by having the edges 25 of the panel 10 at the sides of the opening 12 folded in through the opening in the frame and up against its under surface, as shown in Figures 3 and 4. At the ends of the opening 12 in the panel, the edges 26 of the panel are merely folded down into the opening in the frame 24, as shown in Figure 2, and serve to hide the frame and prevent endwise movement thereof.

Each of the doors 14 is formed of a piece of sheet metal having the same curvature as the track 13 and having its ends 27 folded under, as shown in Figure 2. The folded ends 27 of the doors serve to retain the ends of springs 28, which are located one along each edge of each door within the track 13, and which are each formed to curve down at one or two places into resilient contact with the lower flange 13b of the channel-shaped track 13, as shown in Figure 2. The springs 28 serve to press the doors 14 resiliently up against the upper flanges 13a and to hold them frictionally in any position to which they may be moved. Each door is provided with a handle 29 near its inner end, the handles 29 serving not only as a means for conveniently moving the doors but also being adapted to engage the ends 26 of the opening in the panel and to act as stops to prevent the doors from being opened beyond their proper open position. In order to prevent either door from being moved beyond the center of the opening 12 in the panel, a small lug or stop 30 is struck out of the sheet metal forming one of the channels 13 and prevents either of the two doors 14 from moving beyond that point.

From the foregoing, it may be seen that I have provided an ash receiver that is attractive in appearance and simple in construction. It will also be apparent that the various parts of the ash receiver can be formed from sheet metal in suitable dies and that the cost of manufacturing this ash receiver in large quantities will be relatively small, thereby permitting its use on the lowest priced automobiles.

Another form of the invention is shown in

Figures 5 to 8, in which the parts which are the same as the corresponding parts in the device shown in Figures 1 to 4 are identified by the same reference numerals, and in which the parts which differ somewhat from those in the other device are identified by the same reference numerals with the addition of a prime. For example, the door in Figures 1 to 4 is identified by the numeral 14, whereas the door in Figures 5 to 8 is identified by the numeral 14'.

The construction shown in Figures 5 to 8 differs from that shown in Figures 1 to 4 chiefly in that there is a single large door 14' instead of the two smaller doors 14. The door 14' is large enough to close the entire opening 11, and the mounting panel 15' and channels 13' are longer at one end and shorter at the other end in view of the fact that the door 14', when in its open position, projects only to one side of the opening 12. Instead of being provided with a projecting handle 29, the door 14' is formed with a stamped recess 29' near one end for receiving the finger tips and enabling the door to be readily moved from one position to another. Movement of the door 14' beyond its fully open and fully closed positions is prevented by lugs or stops 30' stamped out of the body of the mounting panel 15' and adapted to engage the outside of the finger tip receiving indentation 29' in the door.

As may be seen from Figures 5 and 6, the snuffer 20 is placed near one end of the mounting panel 17' rather than in the center, so that access to the snuffer may be had even when the door 14' is less than half open. This permits the ash receiver, including the snuffer 20, to be used when currents of air are blowing around the interior of the automobile without permitting the air currents to blow into the ash receptacle 17' and blow the ashes that may be therein about the interior of the car.

The use of the finger recess 29' in place of a knob or handle on the door 14' avoids introducing a projection into the interior of the automobile which might be dangerous in case of an accident, while still providing a convenient means for operating the door 14'.

It will be apparent that the mounting panel 15' and the tracks 13' need not extend to the side quite as far as the end of the door 14' in its open position, for the end of the door 14' may overhang a short distance without being the cause of any objectionable rattles.

A third form of the invention is shown in Figure 9, in which the parts which are the same as the corresponding parts in the form shown in Figures 5 to 8 are identified by the same numerals. In this form of the invention, the web 15' of the mounting plate is omitted, and the spring fingers 19'' for holding the receptacle 17' are made integral with the lugs 21'' which are fixed to and support the channels 13''. The lugs 21'' are fixed to the panel 10 through the frame 24, and thus the channels 13'' are held in the correct positions.

While I have shown only a few particular embodiments of my invention, it will, of course, be understood that I do not wish to be limited thereto, since many modifications may be made, and I, therefore, contemplate by the appended claims to cover all such modifications as fall within the true spirit and scope of my invention.

I claim as my invention:

1. In an ash receiving assembly, the combination of a main panel having an ash receiving

opening therein, a retaining frame surrounding said opening at the inner face of said main panel, inwardly bent lips in the main panel at the edges of said opening arranged to engage said frame to secure it in position, lug members secured to said frame, ears secured to said lugs, a mounting panel mounted on said ears whereby said mounting panel is secured to said main panel through said frame to afford an uninterrupted outer surface on said main panel, said mounting panel extending beyond the edges of the opening in said main panel, an opening in said mounting panel, said opening being substantially aligned with the opening in said main panel, the edges of said mounting panel at said opening therein being arranged to receive co-engaging lips of an ash receptacle insertable through said opening and having yieldable fingers formed thereon for engaging the sides of said receptacle, said mounting panel being formed toward its outer edges to afford tracks having open sides, said tracks being formed so that the open sides thereof oppose one another, lie inwardly of adjacent opposed edges of the opening in said main panel when said mounting member is secured in position and so that one wall thereof is substantially co-extensive with the outer surface of said main panel, closure means mounted in said tracks for slideable movement therein, opposed edges of said closure means being bent inwardly, yieldable means held on the edges of said closure means by said inwardly bent portions for retaining said edges in tight sliding engagement with said tracks, said mounting panel with said tracks extending across the opening in said main panel so that the outer surface of said closure means is positioned co-extensive with the outer surface of said main panel when the closure means is positioned across said opening and being formed arcuately rearwardly thereof toward the edges of said opening and rearwardly away from the inner face of the main panel.

2. In an ash receiver, a mounting member comprising a pair of spaced channels having opposed open faces connected by a web offset below said channels and having an aperture centrally located therein, an ash receptacle mounted in said aperture and depending below said web, cover means located above said web and said receptacle and having edges thereof slidably mounted in said channels, and resilient means in said channels extending between said edges and the lower side of said channels for holding said edges in frictional engagement with the upper sides of said channels.

3. In an ash receiver, a mounting member comprising a pair of spaced channels having opposed open faces connected by a web offset below said channels and having an aperture centrally lo-

cated therein, an ash receptacle mounted in said aperture and depending below said web, a cover member located above said web and said receptacle and having edges thereof slidably mounted in said channels, and spring means disposed under and attached to the edge portions of said member extending into frictional engagement with the lower sides of said channels.

10 4. An ash receiver comprising a generally horizontal panel having a rectangular aperture therein, mounting means comprising a pair of opposed spaced channels, said channels extending along the sides of said rectangular opening in said panel and supported thereby and the ends of said channels extending behind said panel from the ends of said rectangular opening, an ash receptacle detachably secured to said mounting means and having a snuffer therein in close proximity to one end, and a member slidably mounted in said channels for closing said aperture in said panel and for covering said receptacle, said member being arranged to move away from the snuffer end of said receptacle as it is initially opened, whereby upon a slight opening of said member said snuffer is exposed for use.

5 5. An ash receiver comprising a generally horizontal panel having a rectangular aperture therein, a pair of inwardly facing channels extending along opposite sides of said aperture, said channels curving rearwardly from the rear side of said panel and extending beyond said aperture and behind said panel at both ends of said aperture, a receptacle mounted below said channels and accessible through said opening and between said channels, aperture closing means including a pair of members having the edges thereof slidably received in said channels, spring means carried on each of members resiliently and frictionally engaging said channel, and a lug struck in from one of said channels and forming a stop therein between said members, said stop being located on the centerline of said aperture and determining the meeting line of said members.

45 6. In an ash receiver, a mounting member comprising a pair of spaced channels having opposed open faces connected by a web offset below said channels and having an aperture centrally located therein, means for retaining an ash receptacle in said aperture, and cover means slidably mounted in said channels for covering said receptacle and closing the aperture in said web, said cover means including a downwardly depressed finger receiving portion for manipulation of said cover means, and said web including an upstanding portion adapted to be engaged by said downwardly depressed portion of said cover means and to cooperate therewith and act as a stop.

JOHN VISSER.
